(57) **CLAIM**

The ornamental design for a remote controller with graphical user interface, as shown and described.

DESCRIPTION

FIG. 1 is a front, top and right side perspective view of a remote controller with graphical user interface, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged screen image thereof; and,

FIG. 9 is a reference enlarged screen image showing in use. The broken lines showing the remote controller and portions of the graphical user interface in the drawings form no part of the claimed design.
